W. Sanderson's "Frontin and Room"

Design No 2497.

Dec. 497

Wm L. Sanderson of Troy N. Y.
assignor to

R. R. Finch Jr. & R. R. Finch Jr. of Peekville N. Y.

Letters Patent No 4,97 Dated Sept 7. 1852

mmmmmm

The schedule referred to in these Letters Patent and making part of the same

mmmmmm

To all whom it may concern

Be it known that William L. Sanderson

of Troy in the County of Rensselaer and State of New York have invented a new ornamental design for a cast iron Parlor stove which I denominate the

"Franklin Coal Burner"

and I do hereby declare that the following is a full and exact description of the same reference being had to the accompanying drawings forming part of this specification in which.

Fig 1 is a side elevation of the stove complete.

Fig 2 a front elevation of the same

Fig 3 is a plan of the bottom plate and

Fig 4 a plan of the top plate

Fig 5 is a plan of the water evaporating vase

Fig 6 is a profile section of the front of the stove in the red line ++ of Figure 2

Fig 7 a profile section of either the front or sides in the red line x x of Figure 1 and

Fig 8 a half profile section of the sides or back in the red line ** of Figure 1

Fig 9 is a full view of one of the feet

Similar letters of reference indicate corresponding portions of the ornament in each of the several Figures

The stove is of square form with panelled front, sides, and back. In the centre of the lower panel of the sides and back which are square there is a bas relief ornament A of flowers and leaves (see Figure 1); this is surrounded by a line a of lozenge and diamond shaped projections, then by an ogee b and externally by a line c of wavy ornament. The part of the front plate which corresponds in position with the above described panels is occupied by a pair of doors whose panels are intended to be filled with mica and whose stiles have a strong d of ornaments similar to a, all around them and outside, a line e of wavy ornament similar to b. The

upper panels of the front and sides (the front being the fire door) are intended to have windows the frames of which are ornamented by a string of ornaments *i* similar to *a* (see figure 1). The tiles outside *e* have an ovolو *f* running round them and outside the ovolو the plate is scaped and the scape ornamented with a wavy ornament *g*. The part of the back which corresponds in position with the upper panels is occupied by the chimney opening.

On the sides, front and back of the stove near the corners are two ornaments extending from the cornice around the top nearly to the bottom plate; these ornaments consist each of a congeated ribbon *B* having a raised pendant-leaf *c* at the top part a leaf and lozenge ornament *D* near the middle and a pendant-leaf and flower ornament *E* at the bottom, this is best shown in Figure 1. The upper part of the body is surrounded by a cornice *F* whose form is best shown in Figure 1.

The top plate has a raised ornament running all round it near the edges in the form of a square frame: of this ornament one fourth only is shown in Figure 4, but this is sufficient to explain the whole as the sides and corners are all alike: from each corner springs a cluster *G* of vine leaves and fruit reaching nearly to the middle of the sides: in the middle of each side is a star *h*, which is surrounded by a hexagonal fillet *j* which extends to and terminates in the ornament *G*. The cover has a circular base *I* in the centre which is ornamented by radiating leaves this is surrounded by a small moulding *K* in the form of a square and the whole is surrounded by an ogee *l*, which terminates in the above described ornament of the top plate upon the ogee *l* there is a small wavy ornament *m*.

The bottom plate is surrounded by an ovolو inside which is a scape and inside the scape an ^{other} ovolو; the scape is ornamented all around in the manner shown at *m* in Figure 3 the same ornament is carried round the ash pit cover. The register is ornamented with a diamond and lozenge ornament *o*, similar to *a*, *d*, and *i*.

The water vase *T* and cover *J* are octagonal the ornaments on their several sides will be better understood by reference to figures 1 and 5; than by any description.

The form of feet *P*, *K* and the bas relief ornaments upon them are shown in Figures 1, 2 and 9. The front plate of the ash pit has a single panel which has a bas relief ornament *I*, of vine leaves and fruit of a similar character to the ornament *G* on the top plate.

What I claim as my invention and desire to secure by Letters Patent is -

The within described design configuration and general arrangement of the forms

3

Des. 497

ornaments and mouldings upon the stove as a whole and upon the following parts individually, the side, back, and front plates, doors; bottom plate; top plate and cover; water vase; ewer and front of ash pit; the whole being shown in the accompanying drawings.
